UNITED STATES PATENT OFFICE

94,581

DESIGN FOR A DISPLAY CARTON FOR PAINTBRUSHES

Howard M. Ward, Baltimore, Md.

Application November 23, 1934, Serial No. 54,143

Term of patent 3½ years

To all whom it may concern:

Be it known that I, Howard M. Ward, a citizen of the United States, residing at the city of Baltimore, in the State of Maryland, have invented a new, original, and ornamental Design for Display Cartons for Paint Brushes, of which the following is a specification, reference being had to the accompanying drawing, forming part thereof.

I claim

The ornamental design for a display carton for paint brushes as shown.

In testimony whereof I have hereunto set my hand this 16th day of November, 1934.

HOWARD M. WARD.
